(57) **CLAIM**

The ornamental design for the tonal selection pad, as shown and described.

DESCRIPTION

The tonal selection pad is a surface design that identifies tone-generating buttons on a musical instrument.

FIG. 1 is a top view of a tonal selection pad applied on a piano-shaped musical instrument showing our new design. FIG. 2 is an enlarged presentation of the tonal selection pad shown in FIG. 1.

FIG. 3 is a top view of a second embodiment of the tonal selection pad applied on a guitar-shaped musical instrument; and, FIG. 4 is an enlarged presentation of the tonal selection pad shown in FIG. 3.

The broken line showing of piano and guitar-shaped musical instruments is intended to illustrate environment only, and forms no part of the claimed design.
